FASTENING DEVICE FOR FLOOR COVERINGS

Filed March 29, 1927

UNITED STATES PATENT OFFICE.

WILLIAM C. JOSEPH, OF FORT WORTH, TEXAS.

FASTENING DEVICE FOR FLOOR COVERINGS.

Application filed March 29, 1927. Serial No. 179,220.

This invention relates to new and useful improvements in fastening devices for floor coverings.

The principal object of the invention is to provide a fastening device for use in connection with concrete or other floors into which nails can not be driven, for securing carpets, rugs and the like in place in a ready and expeditious manner, as well as in a new and novel way.

This invention, while subsequent to my invention set forth and covered in my application filed February 8, 1927, Serial No. 166,640, and possessing certain features and advantages not set forth in the previous application is not primarily an improvement on the aforesaid invention, but is a companion invention thereto.

An important object of the invention is to provide a fastening device which may be formed so as to be used in buildings already constructed, or which may be formed to be installed in buildings under construction, thus becoming a permanent fixture.

A particular object of the invention is to provide a fastening device for fastening the edges of the floor covering in close contact or relation with the side walls of the room, but permitting the covering to be removed if desired.

Another very important object of the invention is to provide a fastener comprising an over-hanging hook having a down-turned bill in connection with an upwardly directed hump or boss co-acting with the hook to fasten the floor covering in place.

Another object of the invention is to provide a fastening device comprising a pair of hooks over-hanging humps thereunder and connected by a bridle bar having a central hump for co-acting with the other humps for fastening the floor covering in place.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a front elevation of a fastening device constructed in accordance with my invention.

Fig. 2 is a sectional detail showing the said fastening device in position for fastening floor coverings in place,

Fig. 3 is a plan view of the device shown in Fig. 1 and in position against a wall,

Fig. 4 is a plan view of another form of fastener,

Fig. 5 is a front elevation of said fastening device,

Fig. 6 is a sectional view showing the device in position and fastening floor coverings in place,

Fig. 7 is a sectional detail showing another form of fastening device, and

Fig. 8 is a front elevation of the same.

In the drawings the numeral 10 designates an up-right post or support. This post is doubled upon itself at 11 and has a horizontal hook 12 directed outwardly therefrom. A base bar 13 extends outwardly from the bottom of the post and the hook relatively overhangs this bar. Intermediate the ends of the hook, the base bar is provided with an upwardly bent boss or hump 14.

The hook 12 has at its outer end a downwardly bent and inwardly directed bill 15, which is preferably reduced to a sharp point. It will be seen that when the edges of the floor covering A and the padding B are shoved under the bill 15, they will be displaced upwardly by the hump 14, thus causing the said bill to bite more deeply into the covering A and prevent its outward displacement.

The invention in its simplest form may constitute a base bar with a hump and a hook supported relatively above the base bar and having a down-turned bill for engaging in the floor covering and co-acting with the hump, or it may comprise a post having an outwardly directed hook with a down-turned bill and a suitable member for securing the device in place. It would be possible to duplicate this construction and arrange the fastenings in various manners. In the following description, I have pointed out some of the ways in which this may be done.

In Figs. 1, 2 and 2 the base bars 14 are extended outwardly beyond the bills 15 of a pair of spaced hooks 12. The outer ends of the base bars are bent into a bridle bar 16 connecting the same. This bridle bar is bent inwardly and upwardly to form a hump 17 at its center having about the same elevation as the humps 14; this, however, is subject to variation. This hump will support the floor covering between the hooks and assist in causing the bills to engage in said covering; however, the invention is not to be limited either to the use

of the bridle bar or a bridle bar having a hump. It will be seen that the fastening device which has been illustrated may be formed from a single piece of wire of suitable material, but I do not wish to be limited to the manufacture of the fastening device from wire.

This particular form may be used wherever found practical, but particularly where the side walls have been previously constructed. The fastening device is placed with its bars 13 resting upon the floor D and with its posts 10 in contact with the face of the side wall E. The base board C is then placed with its lower edge resting on the hooks 12 and holding the posts 11 against the wall. By this arrangement, the fastening devices are secured in place and are concealed. The floor covering A and padding B are pushed in under the bills 15 and over the humps 14 and 17, thus being securely fastened.

In Figs. 4, 5 and 6 I have shown a form adapted to be embedded in the walls of a new or old building. In this form, the upright posts 10' are comparatively short and the hooks 12' are bent outwardly from the upper ends of said posts. Each hook has a down-turned and inwardly directed bill 15'. The base bars 13' have humps 14' and are connected by a bridle bar 16' having a hump 17'. From the bottom of each post a shank 18 is directed oppositely from the base bar and is provided with one or more humps or convolutions 19. The shank also includes a return member 20 bent parallel thereto and forming a continuation of the base bar. This form may also be made from a single piece of wire, as is evident, but I do not wish to be limited to such a construction.

In applying the fastener, it is placed upon the floor D with its posts 10' in position to contact with the face of the side wall E, while the parts 18, 19 and 20 of its shank are located to be embedded in the wall E when the same is constructed. The shank could also be used under door sills and in other places, and also could be embedded in an old wall if the same was dug out to receive the shank and then filled after the fastener had been placed in position. A base board (not shown) could be placed over the hooks 12' or it could be omitted. The manner of attaching the floor covering is the same.

In Figs. 7 and 8 I have shown a device comprising a pair of upright posts 10^a, each having a hook 12^a directed outwardly from its upper end and provided with a down-turned bill 15^a. A bridle bar 16^a is arched between

the posts and in this instance forms a shank. The ends of the bar are bent into the lower ends of the posts. It is secured in place like the form shown in Fig. 1.

Various changes in the size and shape of the different parts, as well as modifications and alterations, may be made within the scope of the appended claims.

What I claim is:

1. A fastening device for floor coverings comprising, an upright post, a base member directed outwardly from the base of the post, 70 a hook directed outwardly from the post and spaced above the base member, a down-turned bill on the outer end of the hook, a hump in the base member, and a shank extending from the post oppositely from the base member 75 and hook.

2. A fastening device for floor coverings comprising, a pair of upright posts spaced apart, elevated hooks directed outwardly from the posts and each having a down-turned 80 bill, and a bridle bar connecting the posts, all of said parts being integral.

3. A fastening device for floor coverings comprising a base member, a hook having a down-turned bill and relatively spaced above 85 the base member, a projected retaining member for supporting the hook above the base member with the bill out of contact therewith, and a hump in the base member relatively underlying the hook.

4. A fastening device for floor coverings comprising a retaining post including parallel members, a base member directed outwardly from one of said post members, a hook directed outwardly from the other post member 95 and having a bill supported above the base member, and an upwardly bent portion in the base member cooperating with said bill.

5. In a fastening device for floor coverings, a pair of retaining posts, a pair of spaced 100 hooks extending outward from said posts and having down-turned bills, base members extended from said posts and relatively underlying the hooks, and a hump in each base member.

6. In a fastening device for floor coverings, a pair of retaining posts, a pair of spaced resilient hooks extending from said posts and having down-turned bills, base members from the posts relatively underlying the hooks, and an inwardly extending bridle bar connecting the base members intermediate the bills and posts.

In testimony whereof I affix my signature.

WILLIAM C. JOSEPH.
